COIN-CONTROLLED MACHINE

Harry S. Benjamin, Poughkeepsie, N. Y.

Application October 4, 1940, Serial No. 359,755

17 Claims. (Cl. 194—93)

This invention relates to coin-controlled machines.

One object of this invention is to provide a coin-controlled machine which permits the machine to be operated through a partial stroke or cycle when no coin has been placed in the machine, so as to enable the clearing of the machine of slugs, false coins, coins of the wrong denominations, etc.

Another object is to provide a coin-controlled machine wherein means is provided for permitting the operator to change his mind and get his coin back even after he has inserted the coin and operated the machine a predetermined part of an operating cycle.

Another object is to provide a machine as set forth in the last mentioned object, wherein means is provided for retaining the coin in the machine after the machine has been operated beyond the said predetermined part of the operating cycle.

Another object is to provide a coin-controlled machine wherein means is provided for preventing the operator from operating the machine rapidly enough to cause ejection of the merchandise before the coin can be dropped into the coin box, thereby preventing an extremely rapid operator from using the same coin to obtain two or more pieces of merchandise or to operate in a machine through two or more operating cycles.

Another object is to provide a coin-controlled machine wherein means is provided for preventing jamming or wedging of the coin in its operating position in the machine.

Another object is to provide a coin-controlled machine having means permitting only a partial stroke or cycle of the machine followed by a return of the coin to the operator in the event that the coin-controlled mechanism is incapable of carrying out the purpose for which the coin was inserted, as, for example, when the supply of merchandise in a vending machine is exhausted.

Another object is to provide a coin-controlled machine having means for forcibly ejecting the coin either into the coin return chute or into the coin box, thereby preventing the sticking or wedging which occasionally occurs in machines wherein gravity alone is depended upon for ejecting the coin.

Another object is to provide a coin-controlled machine as set forth in the preceding objects wherein all of the operations of the machine are carried out by the motion of a single operating member, thereby requiring the operator to manipulate only one member rather than a plurality

of such members as in certain prior art machines.

In the drawings:

Figure 1 is a side elevation of a preferred embodiment of the coin-controlled machine of the invention, with the operating bar in its upper or starting position but with the coin deposited in its operating position initially.

Figure 2 is a side elevation of the machine shown in Figure 1.

Figure 3 is a rear side elevation of the upper part of the machine shown in Figure 1, partly broken away to disclose the coin-holding rollers.

Figure 4 is a side elevation similar to the upper part of Figure 1 but showing the position of the parts shortly after the operating cycle has been started.

Figure 5 is a front elevation of the lower part of Figure 2, with the parts corresponding in position to the position of the parts in Figure 4, and at the same point in the operating cycle.

Figure 6 is a side elevation similar to Figures 1 and 4, but with the working parts in the positions which they occupy at the end of the predetermined part of the working cycle within which the operator may change his mind and obtain the return of his coin.

Figure 7 is a side elevation similar to the lower part of Figure 2 but with the working parts in positions corresponding to the similar point in the operating cycle as Figure 6.

Figure 8 is a side elevation similar to Figures 1, 4 and 6, but with the working parts at the end of the operating cycle and with the coin falling downward into the coin box.

Figure 9 is a front elevation similar to the lower part of Figure 2 but with the working parts in the positions corresponding to the end of the operating cycle, as in Figure 8.

Figure 10 is a side elevation similar to Figure 1 but showing the operating parts in position on a return stroke where the operator has changed his mind before completing a working stroke of the machine and is having his coin returned to him.

Figure 11 is a side elevation similar to Figure 1 but showing positions of the working parts while the machine is being operated without a coin for the partial working stroke permitted by the mechanism.

Figure 12 is a front elevation similar to the lower part of Figure 2 but showing the working parts in positions corresponding to the point in the operating cycle reached by the mechanism in Figure 11.

Figure 13 is a vertical section through the operating bar and its associated mechanism taken along the line 13—13 in Figure 1.

Figure 14 is an approximately horizontal section at the level of the coin holding rollers, taken along the line 14—14 in Figure 1.

Figure 15 is a horizontal section taken along the line 15—15 in Figure 1.

General arrangement

In general, the coin-controlled machine of the invention is intended for use with vending machines or other coin-operated machines intended to perform services or provide amusement for the operator. In the machine of the present invention, the coin is deposited in a position where it is supported by three rollers mounted on three separate levers. These rollers are operatively connected or related to an operating bar which is set in motion when the operator turns the operating knob or moves an operating member corresponding to the operating knob.

The operating bar is provided with various cams which actuate the coin roller levers in various ways. After a coin has been inserted and a partial operating cycle has been accomplished, the operator may change his mind and get his coin back if he releases the operating knob or other operating member. In that event, the mechanism moves one or more of the coin holding rollers to permit the coin to fall into the coin return chute whereby it is returned to the operator. If, however, the operator continues the operating cycle beyond this predetermined point, the mechanism prevents the return of the coin and carries out the complete operating cycle, thereby guiding the coin into the coin box and ejecting the mechanism or performing the service for which the coin was deposited. In this event, one of the coin holding rollers moves in a different direction to guide the coin into the coin box rather than into the coin return chute, as in the partial cycle where the operator changed his mind and sought the return of his coin.

The machine of the present invention also permits a partial stroke or cycle when no coin whatever has been deposited therein. This enables the machine to be cleared of slugs, false coins or coins of the wrong denominations.

Construction of coin-controlled machine

Referring to the drawings in detail, Figure 1 shows a preferred embodiment of the coin-controlled machine of the invention as consisting of a frame 20 having a plate 21 secured thereto, as by the flange portion 22 and screws 23. The plate 21 projects forwardly from the frame 20 and has secured thereto, as at 24, a second plate 25. The two plates 21 and 25 are placed face to face with each other and are held closely together.

Secured as at 26 to the plate 21 is a coin chute 27 aligned with a coin slot 28 in a coin window 29 mounted in the front wall 30 of the machine. The coin chute 27 is inclined downwardly and consists of a generally inclined portion 31 and a vertical portion 32. The vertical portion 32 terminates immediately above a closure member 33 secured as at 34 to the plates 21 and 25. The closure member 33 is spaced apart from the plate 21 by a space sufficient for the passage of a coin, and for that purpose (Figure 3), it is provided with flanged front and rear walls 35 and 36 respectively. The retaining member 33 is bifur-

cated in its lower parts, and is there provided with a coin retaining chute 37 near the front of the machine and a coin returning chute 38 at the rear thereof. The division between the two chutes 37 and 38 are made by means of the inclined flanged inner walls 39 and 40 respectively, so that a coin which falls upon the inclined wall 39 is guided downwardly into the coin box and is retained by the machine, whereas a coin falling upon the inclined flange 40 is guided downwardly into the coin return chute 38 and is returned to the operator.

The closure member 33 at its upper end is provided with a coin inlet port 41 (Figure 3) communicating with the lower end of the vertical portion 32 of the coin chute 27. For purposes of simplicity, the coin chute 27 is shown as leading directly into the chamber 42 (Figure 14) within the closure member 33. In actual practice, however, the machine is additionally provided with so-called coin-testing mechanism interposed between the coin chute 27 and the subsequent mechanism, whereby slugs, washers, buttons, coins of the wrong denominations, and other improper checks or coins are eliminated, thus permitting only proper coins or checks to pass into the chamber 42 within the closure member 33. This coin testing mechanism is well known to those skilled in the art, and forms no part of the present invention.

After passing downwardly through the passages 31 and 32 of the coin chute 27, the coin 43 comes to rest upon a bottom coin-holding roller 44 and against either the front coin-holding roller 45 or the rear coin-holding roller 46. The bottom coin-holding roller 44 is rotatably mounted upon a pin 47 (Figures 3 and 14) mounted in the upper end of the bottom roller lever 48. The latter at its upper end is provided with a projection 49 and at its mid-point is provided with a second projection 50 adjacent the pivot pin 51 upon which the bottom roller lever 48 is pivotally mounted and which in turn is mounted in the vertically reciprocable operating bar 52. The lower end of the bottom roller lever 48 is provided with a pin 53 to which is secured one end of a spring 54, the opposite end of which is secured to a pin 55 mounted near the lower end of the operating bar 52.

The rear coin-holding roller 46 is rotatably mounted upon a pin 57 mounted at the mid-portion of the rear roller lever 58, the lower end of which is pivotally mounted upon the pivot pin 59 secured to the plate 25 (Figures 1 and 3). The upper end of the lever 58 is provided with a head 60 carrying a projection or cam follower 61 which engages the cam portion 62 of the lower operating bar cam 63. The cam 63 is fixedly secured to the operating bar 52 and serves to control the motion of the rear coin roller lever 58 as the operating bar 52 is moved downward by the operator or upward by a coil spring 64 anchored as at 65 to the plate 25, and at its opposite end secured to the member 66 attached as at 67 to the lower end of the operating bar 52 (Figure 1). The cam follower portion 61 is urged against the cam portion 62 (Figure 1) by means of the coil spring 68 secured as at 69 to the head 60 of the lever 58 and at its opposite end to the pin 70 mounted on the operating bar 52.

The front roller 45 (Figure 3) is rotatably mounted upon a pin 71 which in turn is mounted at the upper end of the front coin roller lever 72. The latter is in bell crank form, and is pivotally mounted upon the pivot pin 73 mounted

on the plate 25 (Figure 1). The upper arm 14 of the front roller lever 12 carries an ear 75 to which one end of a spring 76 is attached, the other end being connected to an ear 77 upon the front cam lever 78. The lower arm 79 of the front roller lever 12 is provided at its end with a pivot pin 80 (Figure 1) carrying a roller 81 adapted to be engaged by the projection 49 of the bottom coin roller lever 48 when the latter is swung in that direction on the return stroke of the operating bar 52 by the engagement of the upper edge of its projection 50 with the lower edge of the nose 82 of the yieldable tripping lever 83 (Figure 1) of bell crank form mounted upon the pivot pin 84 secured to the plate 25. The lower end of the tripping lever 83 is provided with an ear 85 to which one end of a spring 86 is secured, the opposite end being secured to a pin 87 mounted on the operating bar 52. The spring 86 normally urges the tripping lever 83 against a stop pin 88 mounted near the lower end of the plate 25 (Figure 1) but permits the trip lever 84 to swing forwardly when the projection 50 engages the nose portion 82 of the tripping lever 83 on its downward stroke. On its upward stroke, however, the upper edge of the projection 50 engages the lower edge of the nose 82. Since the nose 82 is incapable of moving because of the stop pin 88, this engagement swings the bottom roller lever 48 forward so that its upper projection 49 engages the roller 81 of the front roller lever 12 and swings the latter rearwardly.

The bottom roller lever 48 is also adapted to be swung rearwardly by the engagement of the lower edge of its projection 50 with the pin 89 mounted on the plate 25 when the operating bar 52 nears the lower end of its working stroke. Thus the forward swinging of the bottom roller lever 48 on the upward or return stroke of the operating bar 52 serves to drop the coin downward against the inclined flange or wall 40, whence it is deflected into the coin return chute 38 and returned to the operator. On the other hand, the rearward swinging of the bottom roller lever 48 by the engagement of the lower projection 50 with the pin 89 permits the coin 43 to fall downward against the inclined flange or wall 39, whence it is deflected into the coin retaining chute 37 and thereafter into the coin box of the machine.

Also secured to the end 77 on the front cam lever 78 is one end of a spring 90, the opposite end of which is anchored to the pin 70 mounted on the operating bar 52. The lower end of the front cam lever 78 is pivotally mounted upon the same pivot pin 73 which pivotally supports the front roller lever 12. The mid-portion of the front cam lever 78 is provided with a projection or cam follower 91 (Figure 8) which engages the cam portion 92 upon the forward end of the cam 63 mounted on the operating bar 52. Adjacent the cam follower 91 on the front cam lever 78 is an adjusting screw 93 carrying a non-rotatable eccentric sleeve 94 (Figure 1) which is engaged by the lower arm 95 of a bell-crank lever 96 pivotally mounted upon the pin 97 secured to the plate 25 and having its upper arm 98 engageable by a pin 99 mounted on the upper end of the operating bar 52. When the operating bar 52 nears the lower end of its operating stroke, but beyond the point where the operator may change his mind and have his coin returned, the pin 99 engages the upper arm 98 and swings the lower arm 95 of the bell crank

lever 96 forwardly against the sleeve 94, swinging the front cam lever 78 forwardly and likewise permitting the front roller lever 12 to swing forwardly under the influence of the coil spring 76. By loosening the adjusting screw 93, the eccentric sleeve 94 may be rotated to a different position and then secured in this position by tightening the screw 93. This enables the motion of the front cam lever 78 to be properly synchronized with the operation of the remainder of the mechanism.

The upper end of the front cam lever 78 carries a stop pin 100 which is adapted to swing beneath the cross member 101 fixedly secured to the operating bar 52 near its upper end. This arrangement halts the operating bar 52 at a predetermined position when the machine is attemptedly operated without a coin. The motion of the operating bar 52 as a whole is guided and also limited by slots 102 and 103 near its opposite ends and serving to receive pins 104 and 105 mounted in the upper and lower portions respectively of the plate 25.

The plate 21 along its lower edge is provided with slightly bent, coin-deflecting portions 106 and 107 cooperating with the adjacent portions of the closure member 33 to deflect the coin either into the coin return chute 38 or into the coin-retaining chute 37 as the case may be. The plates 21 and 25 are formed with elongated apertures or slots 108, 109 and 110 for respectively permitting the motion of the coin-holding rollers 44, 45 and 46 as well as permitting the rollers to project therethrough into the chamber 42 formed between the plate 21 and the closure member 33 (Figure 14).

Operating mechanism

The operating bar 52 may be reciprocated in any desired manner by any suitable operating member manipulated by the operator. For purposes of illustration, the machine as shown is provided with actuating mechanism similar to that disclosed in United States Letters Patent No. 2,010,911 to H. S. Benjamin, dated August 13, 1935, for a Vertical column vending machine. Reference is made to this patent for a vending machine to which the coin-controlled machine of the present invention may be attached for vending articles such as candy, gum, food, etc.

For this purpose a link 111 (Figures 1 and 2) is provided with an ear 112 pivotally mounted upon the screw 67 in the lower end of the operating bar 52. The link 111 is slotted as at 113 to receive a guide pin 114 mounted in the supporting plate 115. The supporting plate 115 is secured as at 116 to the forward flange 117 of the angle plate 118 (Figure 1), the rearward flange 119 of which is secured as at 120 to the frame or rear wall 20. The latter is provided with a hole 121 in which is journaled an operating shaft 122, the forward end of which is journaled in an aperture 123 in the front wall 124, and is provided with an operating knob 125 mounted thereon. The operating knob 125 is the external part which is grasped by the operator for operating the machine.

Mounted on the operating shaft 122 is a cam 126 (Figure 1) of roughly triangular shape and arranged to engage a roller 127 mounted on a pin 128 carried by the lower end of the link 111. The latter is slotted as at 129 (Figure 2) in order for it to accommodate the operating shaft 122. As a consequence, when the knob 125 is rotated, and with it the cam 126, the

engagement of the cam-follower roller 127 with the cam 126 causes the link 111 and operating bar 52 to be drawn downward. When the knob 125 is released, however, the spring 64 assists in retracting the operating bar 52 and link 111. At the same time, however, the knob 125 and operating shaft 122 are returned to their original position by means of a spring 130 secured at one end to the pin 131 mounted in the supporting plate 115 and at its other end passing over a circumferential groove 132 in a disk 133 mounted on the operating shaft 122 and anchored by the screw 134 (Figure 1).

Also mounted on the operating shaft 122 is a quadrant ratchet 135 resembling a mutilated gear and having ratchet teeth 136 extending only partially around its periphery. The ratchet teeth 136 (Figures 1 and 2) are engageable with a bell crank pawl 137 mounted on the pivot pin 138 secured to the supporting plate 115. One arm 139 of the bell crank pawl 137 is formed and positioned to engage the ratchet teeth 136 whereas the other arm 140 is connected to one end of a spring 141, the other end of which is anchored to the pin 142 mounted on the supporting plate 115.

In order to effect the vending of the merchandise, the shaft 122 is provided with an additional cam 143 mounted thereon and engageable with rollers 144 mounted on pins 145 which in turn are secured to the vending member 146. The latter is slotted as at 147 to accommodate the shaft 122 and at its lower end is provided with a pin 148 to which is secured a spring 149 having its opposite end anchored to the pin 150 mounted on the frame or rear wall 20. The spring 149 constantly urges the rollers 144 against the periphery of the cam 143. The vending member 146 extends upward into the interior of the machine and performs the service for which the operator deposited his coin. In particular, if the machine is a vending machine, the vending member 146 operates a releasing device which releases the article of merchandise, as more fully disclosed in the previously mentioned Benjamin Patent No. 2,010,911 of August 13, 1935. The particular form of this vending mechanism forms no part of the present invention.

Finally, the operating shaft 122 is provided with a disk 151 having a stop projection 152 thereon engageable with the lower end of an arm 153. The latter is pivotally mounted upon a pin 154 carried by a horizontally reciprocable plate 155 having a stop pin 156 secured thereto (Figure 2). The plate 155 is provided with slots 157 for receiving guide pins 158 mounted in the supporting plate 159. The reciprocable plate 155 is connected to the merchandise vending mechanism in such a manner as to be reciprocated to the right when the supply of merchandise has been exhausted in one of the merchandise compartments. When this occurs, the end of the arm 153 is moved into the path of the projection 152 upon the disk 151 and prevents the rotation of the knob 125. In this manner the operator is prevented from operating the machine beyond a certain point when the merchandise has been exhausted. At the same time, however, the machine may be operated to a sufficient point to enable the return of the coin when the knob 125 is released.

Operation

To operate the machine, the operator places a coin 43 in the coin slot 28, whence the coin

passes downward through the coin chute 27 through the port 41 and past suitable fraud-testing mechanism (not shown), halting when it falls upon two of the three rollers 44, 45 and 46 (Figure 3). At this point the various parts occupy the positions shown in Figures 1 and 2.

The operator now rotates the knob 125 and as a consequence draws down the operating bar 52. As the bar 52 and its cam 63 move downward, the projections 61 and 91 on the levers 58 and 78 move inwardly over the top of the cam 63, permitting the coin-holding rollers 45 and 46 to be pulled toward one another by the springs 68 and 90, pushing the coin 43 downward. Meanwhile, the lever 48 carrying the bottom coin-holding roller 44 has been maintained upright by the engagement of the pin 53 with the guide edge 25a of the plate 25 (Figure 3) while moving downward with the operating bar 52. This permits the front and rear rollers 45 and 46 to move over the top half of the center of the coin, thereby holding the coin in suspense but with sufficient pressure of rollers 45 and 46 to press the coin downward on further movement of the bar 52. As the bar 52 moves downward, the projection 50 upon the bottom roller lever 48 engages the nose 82 of the tripping lever 83, pushes it aside, and passes beneath it with a click as the tripping lever 83 returns to its original position. The working parts now occupy the positions shown in Figures 4 and 5.

Thus far the operator can still change his mind and have his coin returned by merely releasing the knob 125, whereupon the springs 130 and 64 return the parts to their original positions of Figures 1 and 2. In the meantime, however, the operating bar 52 moves upward (Figure 10) and the projection 50 on the bottom roller lever 48 engages the lower edge of the nose 82 on the tripping lever 83. Since the latter cannot swing, due to the presence of the stop pin 88, the lever 48 itself is swung toward the front of the machine (Figure 10) and its projection 49 engages the roller 81 on the lower arm 79 of the front roller lever 72, swinging the front coin-holding roller 45 rearwardly as the bottom coin-holding roller 44 moves downwardly. This produces a hammer blow on the coin, thus positively dislodging it and preventing it from becoming wedged between the rollers 44, 45 and 46 during the rapid return of the operating bar 52 by the springs 64 and 130. At the same time, the rear roller lever 58 and the rear coin-holding roller 46 are moved rearwardly by the engagement of the projection 61 thereof with the cam 63 (Figure 10). The coin 43, accordingly, drops through the gap between the oppositely moving coin-holding rollers 44 and 46 and is deflected by the flange 40 into the coin returning chute 38, whence it is returned to the operator. The latter may then insert the coin in the coin chute corresponding to another kind of merchandise.

Let it be assumed, however, that the operator is satisfied with his choice, and rotates the knob 125 as far as it will go. When the shaft 122 has rotated the quadrant ratchet 135 to the point where the pawl arm 139 engages between the teeth 136 of the ratchet 135 (Figure 9), or just beyond the end of the "mind-changing" part of the cycle shown in Figures 6 and 7, the pawl 137 will prevent the return motion of the knob 125 until it has been completely rotated. As the operating bar 52 moves downward to the end of its stroke (Figure 8), therefore, the projection 50 on the bottom coin-holding roller lever 48 engages

the fixed pin 89 and swings the lever 48 and the bottom coin-holding roller 44 rearward, opening a gap between it and the forward coin-holding roller 45 through which the coin 43 drops downward into the coin retaining chute 31 and thence into the coin box of the machine. The front coin-holding roller 45 is permitted to move forward when the lever 78 is forcibly moved forward by the engagement of the pin 99 with the upper arm 98 of the bell crank lever 96, the lower arm 95 of which (Figure 1) engages the sleeve 94 and forces the lever 98 forward as the operating bar 52 approaches the end of its working stroke. This still further widens the gap between the bottom roller 44 and the front roller 45.

While this is occurring, the rotation of the operating shaft 122 rotates the cam 143 (Figure 1) and pulls down the vending member 146, releasing an article of merchandise in the manner set forth in the previously mentioned Benjamin Patent No. 2,010,911 of August 13, 1935. The article thus vended drops down through the vending chute and is withdrawn by the operator. By this time the pawl arm 139 has passed over all of the teeth 136 of the quadrant ratchet 135.

When the knob 125 is released, therefore, the spring 138 acting on the disk 133 rotates the operating shaft 122 and knob 125 backward to their starting positions, while the pawl arm 139 clicks over the ratchet teeth 136 until the ratchet 135 reaches its starting position (Figure 2). Meanwhile, the upward motion of the cam 63 on the operating bar 52 forces the levers 58 and 78 apart and causes the front and rear rollers 45 and 46 to move apart from each other, ready for the reception of another coin.

In case the knob 125 is rotated without the depositing of a coin in the coin chute 31, the machine operates through a part of the operating cycle in the manner previously described. This partial operation enables the machine to be cleared of slugs, buttons, washers or other undesirable articles. As the operating bar 52 moves downward, the projection 91 on the lever 78 moves over the top of the cam 63 and permits the lever 78 to move rearward, causing the pin 100 on the end thereof to move beneath the cross member 101 on the operating bar 52 (Figure 11). This action effectively halts the downward motion of the operating bar 52 in the position shown in Figure 11, and accordingly prevents the rotation of the knob 125 to a position where it will vend merchandise.

While I have shown and described my invention in detail, it is to be understood that the same is to be limited only by the appended claims, for many changes may be made without departing from the spirit and scope of my invention.

What I claim is:

1. In a coin-controlled machine, a movable operating member, a plurality of levers having coin-holding members thereon, said levers being operable by the movable operating member, means for guiding a coin into position with respect to said coin-holding members, a coin returning passageway, and means on the operating member for actuating said levers upon the partial completion of a return stroke of said operating member after the completion of a partial forward stroke of said operating member of less than a predetermined distance for releasing said coin from said coin-holding members and directing said coin into said coin-returning passageway whereby to enable the operator to change his mind and recover his coin after oper-

ating the machine through a partial forward stroke.

2. In a coin-controlled machine, a movable operating member, a plurality of levers having coin-holding members thereon, said levers being controlled by the movable operating member, means for guiding a coin into position with respect to said coin-holding members, a coin returning passageway, and means engageable upon a reversal of stroke of said operating member after the completion of a partial forward stroke of said operating member of less than a predetermined distance for moving one of said levers to direct said coin into said coin-returning passageway whereby to enable the operator to change his mind and recover his coin after operating the machine through a partial forward stroke.

3. In a coin-controlled machine, a movable operating member, a plurality of levers having coin-holding members thereon, said lever being controlled by the movable operating member, means for guiding a coin into position with respect to said coin-holding members, a coin returning passageway, a coin-retaining passageway, and means responsive to a partial stroke of said operating member for moving one of said levers to direct said coin into said coin-returning passageway and responsive to the completion of a stroke greater than said partial stroke for moving another one of said levers to direct said coin into said coin-retaining passageway.

4. In a coin-controlled machine, a movable operating member, a plurality of levers having coin-holding members thereon, said lever being operable by the movable member, means for guiding a coin into position against adjacent said coin-holding members, a coin returning passageway, a coin-retaining passageway, and means responsive to the completion of a predetermined partial stroke of said operating member for moving one of said levers to direct said coin into said coin-returning passageway and responsive to the completion of a stroke exceeding said predetermined stroke for additionally moving said last mentioned lever to direct said coin into said coin-retaining passageway.

5. In a coin-controlled machine, a movable operating member, a plurality of levers having coin-holding members thereon, said levers being operable upon movement of the operating member, means for guiding a coin into position adjacent said coin-holding members, a coin-returning passageway, a coin-retaining passageway, and means responsive to the completion of a predetermined partial stroke of said operating member for moving one of said levers to direct said coin into said coin-returning passageway and responsive to the completion of a stroke exceeding said predetermined partial stroke for moving said last mentioned lever in a different direction to direct said coin into said coin-retaining passageway.

6. In a coin-controlled machine, a movable operating member, a plurality of levers having coin-holding members thereon, said levers being operable by the movable operating member, one of said levers being mounted on and movable with said operating member the other levers acting to retain a coin, a coin returning passageway, and means responsive to a predetermined part of the stroke of said operating member for separating the retaining levers and moving the lever carried by the operating member to direct the coin into said coin-returning passageway.

7. In a coin-controlled machine, a movable operating member, a plurality of levers having coin-holding members thereon, said levers being operable by movement of the operating member, certain levers acting to retain a coin below a coin slot, another of said levers being mounted on and movable with said operating member, a coin retaining passageway, and means responsive to the exceeding of a predetermined stroke for releasing the retaining levers and for moving the lever carried by the operating member to direct the coin into said coin-retaining passageway.

8. In a coin-controlled machine, a movable operating member, a plurality of levers having coin-holding members thereon, said levers being operable upon movement of the operating member, certain of said levers acting to retain a coin below a coin slot and one of said levers being mounted on and movable with said operating member, a coin-returning passageway, and means responsive to a predetermined partial stroke of said operating member for moving the lever carried by the operating member to direct the coin into said coin-returning passageway and responsive to the exceeding of said predetermined partial stroke for differentially moving said member-carried lever to direct the coin into said coin-retaining passageway.

9. In a coin-controlled machine, a movable operating member, a plurality of levers having coin-holding members thereon, said levers being operable upon movement of the operating member one of said levers being mounted on and movable with said operating member, a coin-returning passageway, a coin-retaining passageway, means responsive to less than a predetermined stroke of said operating member for moving the lever carried thereby to direct the coin into said coin-returning passageway and responsive to the exceeding of said predetermined stroke for differentially moving said member-carried lever to direct the coin into said coin-retaining passageway, and means responsive to the motion of said operating member for moving the other levers to retain the coin-holding members in position between the passageways.

10. In a coin-controlled machine, a movable operating member, a plurality of levers having coin-holding members thereon, said levers being operable upon movement of the operating member, one of said levers being mounted on and movable with said operating member to shift a coin in one of its two movable directions, and means responsive to the motion of said operating member for moving the other levers sequentially to position the coin for movement in one of said two directions and to maintain their coin-holding members in engagement with the coin whereby said sequential movement prevents wedging or jamming of the coin in the machine prior to the shifting of said coin.

11. In a coin-controlled machine, a movable operating member, a plurality of levers having coin-holding members thereon, said levers being controlled by movement of the operating member, one of said levers being mounted on and movable with said operating member, the remaining levers acting to retain a coin in a coin chute, a coin-retaining passageway, means responsive to the exceeding of a predetermined stroke for moving the lever carried thereby to direct the coin into said coin-retaining passageway, and means for rapidly moving one of said coin retaining levers

to forcibly eject the coin from the coin-holding members thereof into said passageway.

12. In a coin-controlled machine, a movable operating member, a plurality of levers having coin-holding members thereon, said levers being operable upon movement of the operating member, one of said levers being mounted on and movable with said operating member, means operatively connected to said operating member 10 and responsive to the completion of a working stroke thereof for causing the operation of the coin controlled machine, and means responsive in the absence of articles in the coin controlled machine for locking said operating member against motion beyond a predetermined stroke.

13. In a coin-controlled machine, a movable operating member, a plurality of levers having coin-holding members thereon, said levers being actuated by the operating member one of said 20 levers being mounted on and movable with said operating member, the remaining levers acting to retain a coin in a coin chute, means operatively connected to said operating member and responsive to the completion of a working stroke thereof for causing the operation of the coin controlled machine, means responsive in the absence of articles in the coin controlled machine for locking said operating member against motion beyond a predetermined stroke, a coin-returning passageway, and means responsive to the motion of said operating member through said predetermined stroke for moving one of said levers to release said coin into said coin-returning passageway.

14. In a coin-controlled machine having a retaining passageway and a return passageway, a movable operating member, a plurality of levers having coin-holding members thereon, said levers being actuated by the operating member, one of said levers being mounted on and movable with said operating member, the other levers acting to retain a coin in a coin chute, means responsive to the motion of said operating member for moving the other levers to maintain their coin-holding members in engagement with the coin, means responsive to movement of the operating member for selectively moving the lever carried thereby, and means responsive to a return stroke of said operating member for forcibly and rapidly moving one of said coin retainer levers whereby to forcibly eject the coin from the coin-holding members of said levers into one of said passageways after the lever moving with the operating member has moved to selectively determine the desired passageway.

15. In a coin-controlled machine, a movable operating member, switching mechanism operatively connected to said operating member and operatively responsive to the motion of said operating member through a predetermined stroke for performing said switching operation, a plurality of levers having coin-holding members thereon, said operating levers being operably positioned with respect to the movable member, means for guiding a coin into position adjacent said coin-holding members, a coin-retaining passageway, means responsive to the motion of said operating member for moving said levers to maintain said coin-holding members thereof in engagement with said coin for a predetermined part of said switching stroke, and means for moving one of said levers to release said coin into said coin-retaining passageway prior to the completion of said predetermined switching stroke of said operating member whereby to insure retention of the

coin by the machine before permitting the operation of the machine.

16. In a coin-controlled machine, a movable operating member, switching mechanism operatively connected to said operating member and operatively responsive to the motion of said operating member through a predetermined stroke for performing said switching operation, a plurality of levers having coin-holding members thereon, said levers being controlled by the movable operating member, means for guiding a coin into position with respect to said coin-holding members, a coin-retaining passageway, and means for moving one of said levers to release said coin prior to the completion of said predetermined switching stroke of said operating member and to direct said coin into said coin-retaining passageway whereby to insure retention of the coin by the machine before permitting the switching operation of the machine.

17. In a coin-controlled machine, a movable operating member, a plurality of levers having coin-holding members thereon, said levers being controlled by the movable operating member, means for guiding a coin into position adjacent said coin holding members, a coin return passageway and a coin retaining passageway on opposite sides of said guiding means, one of said levers being mounted on and movable with said operating member to switch a coin toward one of said passageways, and means responsive to the motion of said operating member for moving the other levers prior to the movement of the lever mounted upon the operating member to maintain their coin-holding members in engagement with a coin whereby the retention of said coin will be insured until the lever mounted on the operating rod has been moved toward one of said passageways.
